CHARGE SUPPORT FOR THE BASE OF
COVER-TYPE FURNACES

Harry H. Armstrong, Lakewood, Ohio, assignor to
Lee Wilson Engineering Company, Inc., Cleve-
land, Ohio, a corporation of Ohio

Application February 1, 1945, Serial No. 575,680

13 Claims. (Cl. 263—10)

1

This invention relates to metallurgical furnaces and, in particular, to furnaces of the cover type which are now widely used for the annealing of steel strip or sheets.

In the processing of steel strip, there is a great advantage to be obtained by making coils of the largest size which can be handled conveniently. In the annealing of coils, furthermore, the higher the coils are piled, the smaller the floor space required for processing a given tonnage. According to present proposals, coils may be made as large as 72" in diameter and piled for annealing to a height of over 12'. With smaller coils and lower pile heights, it has been found that the use of a charge support resting on the firebrick laid on the base which is fabricated from structural shapes and sheathing plate, causes rapid deterioration of the brick. In addition, the brick absorbs a great amount of heat which is lost when the charge is cooled.

I have invented a novel charge support particularly adapted for coils of the maximum size and the extreme piling height indicated above, which overcomes the objections to the previous construction and permits the brick layer covering the metal parts of the base to serve for a much longer period than has been possible heretofore. In a preferred embodiment, a charge support according to my invention comprises a table-like member or platform carried on a plurality of supporting posts and having rolling engagement therewith. The posts are pivoted to the metal plate of the base and are thus free to move as may be necessary to accommodate expansion and contraction of the platform with changes in temperature. Certain of the posts have spaced pivot bearings and restrict bodily movement of the platform as a whole. By this construction, the charge is carried on metal supports instead of on the brick layer covering the base.

For a complete understanding of the invention, reference is made to the accompanying drawings illustrating a preferred embodiment which is fully described and explained herebelow.

In the drawings,

Figure 1 is a partial transverse section through a cover-type furnace, the base of which incorporates a charge support according to my invention;

Figure 2 is a partial plan view;

Figures 3 through 5 are sectional views taken along the planes of correspondingly numbered lines of Figure 1; and

Figure 6 is a partial sectional view taken along the plane of line VI—VI of Figure 1.

2

Referring in detail to the drawings, a cover-type furnace 10 includes a base 11 and a cover 12. The base comprises a frame composed of structural members 13 and sheathing plate 14. The cover 12 is indicated somewhat diagrammatically. It is of conventional construction comprising a lining of refractory brick laid up within a binding composed of structural members and sheathing plates. When the cover is lowered over the base, it rests on supports 15.

A charge-supporting platform or table 16 may conveniently comprise a circular casting having a central opening 16a therethrough. The casting has a top 16b, concentric walls 16c and 16d and radial ribs 16e extending therebetween. The platform is supported on a plurality of posts 17 and 18. Both the platform and the posts are preferably composed of a suitable heat-resistant alloy. The posts have rounded heads 19 which fit into concentric grooves 20 formed in flanges 20a extending laterally from the walls 16c and 16d.

The posts 17 and 18 are pivoted to the base 11. A pivot bearing 21 for each of the posts 17 is secured to the plate 14. Each of the posts 18 which are located 90° apart around the circumference of the platform, has two spaced pivot bearings 22 secured to the plate 14 as shown in Figure 6. The posts 18 are bifurcated at their lower ends for cooperation with the bearings 22.

By reason of the pivotal mounting of the posts on the base, they are free to swing through the small angles necessary to accommodate radial expansion and contraction of the platform 16 on heating and cooling. During such movement, of course, the platform rolls on the rounded heads 19 of the posts. The spaced pivot bearings for the posts 18 restrict bodily movement of the platform without limiting its freedom for radial expansion and contraction.

Bolts 23 secure the platform to lateral lugs 18a formed on the posts 18 to prevent the platform from being lifted off of the posts by a crane magnet.

A layer of insulating brick 24 is laid on the plate 14 to protect it from the heat of the interior of the furnace. In laying the brick forming the layer 24, spaces 25 are left about each of the posts 17 and 18 and these spaces are filled with granular thermal insulation which permits the slight angular movement of the posts necessary to accommodate the expansion of the platform. A surface layer 26 of thermal insulation is laid on top of the layer 24.

Furnace bases may be designed to accommo-

date one or more charge supports according to my invention. It is usually more efficient to design a base for a number of piles of coils, say 6 or 8, if the tonnage of strip to be processed is sufficient to fill the furnace on each annealing cycle. It will be evident that charge supports according to my invention may be used in various forms of cover-type furnaces, regardless of the source of heat, i. e., electric resistors, radiant tubes or open flames. I provide the usual inner cover 27 for protecting the charge from the air when the heating cover 12 is removed. I also provide a fan 28 mounted on a shaft 29 projecting upwardly through a tube 30 fixed in the base, for circulating the atmosphere within the inner cover through and around the coils forming the charge.

It will be apparent from the foregoing description that the load imposed on the charge-supporting platform 16 by the weight of the coils disposed thereon, one of which is indicated at 31, is transmitted directly to the structural framework of the base by the posts 17 and 18. While this load is great, the use of a large number of posts, as illustrated, distributes it over a substantial area and prevents the load on each of the pivot bearings 21 and 22 from exceeding a reasonable value. Since the weight of the charge is not carried on the brickwork, the latter is not subject to rapid deterioration and thus has a much longer life than in the construction previously employed. As a matter of fact, the insulating layer 24 is preferably composed of light insulating brick instead of firebrick since no mechanical load is applied thereto. The charge support, furthermore, is free to expand and contract since the posts have rolling engagement therewith and are pivoted to the base. This prevents the development of any stresses resulting from expansion or contraction. At the same time, the charge support is held against excessive bodily movement by the dual bearings for each of the four posts 18 located at the 90° points. Because of the relatively small section of the posts, the heat lost therethrough is small. The surface layer 26 laid on the layer of insulating brick 24 may be of such material as to prevent the absorption by the latter of a substantial amount of heat.

Although I have illustrated and described but a preferred embodiment of the invention, it will be recognized that changes in the details of construction thereof may be made without departing from the spirit of the invention or the scope of the appended claims.

I claim:

1. A charge support for a furnace base comprising a platform adapted to receive the charge, a plurality of posts pivoted to the base supporting said platform, and means for limiting horizontal shifting of the platform.
2. The apparatus defined by claim 1 characterized by said posts having rounded heads providing bearing surfaces for engagement by the platform.
3. A charge support for a furnace base comprising a table-like member, a plurality of posts pivoted to said base, said member resting on

the upper ends of said posts, and means limiting bodily movement of said member.

4. The apparatus defined by claim 3 characterized by said posts being arranged in concentric circles beneath said member.

5. A charge support for a furnace base comprising a table-like member, a plurality of posts below said member having rolling engagement therewith, and pivot bearings on said base for said posts, certain of said posts spaced circumferentially of said member each having a pair of spaced pivot bearings preventing tilting thereof except on the axis through the bearings.

10 6. The apparatus defined by claim 5 characterized by the axes on which said bearings pivot being tangent to an inscribed circle coaxial with said member.

15 7. A charge support for a furnace base comprising a table-like member, recesses in the under side of said member, a plurality of posts having bearing heads seated in said recesses, and pivot bearings on the base for said posts, certain of said posts spaced circumferentially of said member having a pair of spaced pivot bearings.

20 8. A charge support for a furnace base comprising a generally circular platform, a plurality of supporting posts spaced circumferentially beneath the platform, and pivot bearings on the base for said posts, some of said posts having a pair of spaced pivot bearings on the base.

25 9. A charge support for a furnace base comprising a generally circular platform, a plurality of rockable studs supporting said platform, and means for restricting bodily movement of the 30 platform in a horizontal plane.

35 10. The apparatus defined by claim 9 characterized by said studs having their lower ends pivoted to the base.

11. A charge support for a furnace base comprising a platform adapted to receive the charge, and a plurality of posts extending upwardly from the base for supporting said platform, certain of said posts having single pivot bearings on the base and others having two spaced pivot bearings on the base.

40 12. In a base for a cover-type furnace, a platform above the base adapted to receive a charge of material, a plurality of pairs of bearings on said base spaced about a common axis there-through, rocker posts extending upwardly therefrom, said platform resting on said posts, each pair of bearings being disposed on a line substantially tangent to a circle drawn about said axis as a center whereby the posts afford stable support for the platform while permitting free radial expansion and contraction thereof.

45 13. In a base for a cover-type furnace, a platform above the base adapted to receive a charge of material, a plurality of pairs of bearings on said base spaced about a common axis there-through, rocker posts extending upwardly therefrom, said platform resting on said posts, said pairs of bearings being disposed on lines at an angle to each other whereby the posts afford stable support for the platform while permitting free radial expansion and contraction thereof.
